[21] Appl. No.: 482,543

[57] CLAIM

The ornamental design for a deck of golf game cards, as shown and described.

DESCRIPTION

FIG. 1 is a face view of a card in a deck of golf game cards showing my new design;

FIG. 2 is a rear view thereof;

FIGS. 3-6 are face views of the other golf game cards in the deck.

The value number on the cards may vary.
